ALFRED GRIEB, OF ELIZABETH, NEW JERSEY, ASSIGNOR TO THE SINGER MANUFACTURING COMPANY, OF ELIZABETH, NEW JERSEY, A CORPORATION OF NEW JERSEY.

THREAD-CONTROLLING MECHANISM FOR SEWING MACHINES.

Application filed February 7, 1920. Serial No. 356,833.

To all whom it may concern:

Be it known that I, ALFRED GRIEB, a citizen of the United States, residing at Elizabeth, in the county of Union and State of New Jersey, have invented certain new and useful Improvements in Thread-Controlling Mechanisms for Sewing Machines, of which the following is a specification, reference being had therein to the accompanying drawings.

This invention relates to overedge sewing machines of the type embodying a reciprocating needle which passes a loop of thread through the work near the edge thereof, a looper which passes a loop of a second thread through the needle-loop at the under side of the work, and an overedge implement or second looper which, in one form, seizes the looper-loop and carries it over the edge of the work and into position for entry by the needle at the upper side of the work or, in another form, passes a loop of a third thread through the looper-loop and presents said loop of the third thread to the needle above the work.

In machines of the above type, as the needle descends through a previous looper loop presented to it at the upper side of the work, it tightens the previous needle-loop and snubs it around limbs of a looper-loop at the under side of the work so that, as the looper moves forwardly in entering a new needle-loop, the looper-thread is bent sharply around the previous needle-loop. As the forward movement of the looper is depended upon to tighten the previous looper-loop, it will be readily appreciated that a heavy tension must be applied to the looper-thread in order that the looper in its forward movement can pull the sharply bent looper-thread through the previously tightened needle-loop. In overedging bags with rough and easily broken threads, such as those made from jute, it is found that the sharp bend of the looper-thread around the tightened needle-loop practically locks the looper-thread against slipping through the needle-loop, so that even the application of a breaking tension is insufficient to pull the slack from the looper-loop and give the stitches a finished appearance.

An object of the present invention is to provide overedge stitch-forming mechanism which will operate to draw up and properly

set the looper-loops without necessitating the application of a heavy tension to the looper thread or threads thus adapting the machine to the handling of rough and easily broken threads.

Another object of the invention is to provide overedge stitch-forming mechanism which will operate to form and set the stitches, while avoiding a weakening of the sewing threads incident to a harsh reeving or sawing action of one thread against another.

According to the present improvement, a looper-thread take-up or stitch-tightening implement of special construction is combined with the needle and looper. This implement, while moving in opposition to the advancing looper, seizes the looper thread between the looper-eye and the tightened needle-loop and pulls the slack looper-thread from the previous looper-loop in nearly a straight line through the needle-loop, thus avoiding the reeving and locking action incident to tightening one thread while it is bent sharply about another thread. In the embodiment of the invention illustrated, the stitch-tightening implement is combined with a looper which advances in a path inclined forwardly toward the line of feed. This implement seizes the looper-thread close to the previous needle-loop and thereby serves to draw the looper-thread substantially straight or at a very obtuse angle through the needle-loop. The present stitch-tightener is also combined with the second looper or spreader but is actuated from its own eccentric on the main shaft of the machine, whereby a close timing of its movements may be secured relative to the movements of the spreader, in order that the looper thread may be given up as it is required by the spreader during the first part of the lift of the latter, thus avoiding an undue straining of the looper thread while maintaining it closely under control. The timing of the present stitch-tightening implement is preferably such that it seizes the looper-thread while the looper is seizing the new needle-loop and moves in opposition to the looper to pull the slack out of the previous looper-loop after said loop is released by the second looper or spreader. The stitch tightener withdraws as the second looper or spreader cooperates with the

looper. The withdrawal of the stitch-tightener is timed so that the looper thread is maintained under control but is not subjected to undue strain.

5 In the accompanying drawings, Fig. 1 is a fragmentary front side elevation of a machine embodying the invention. Fig. 2 is a fragmentary front end elevation of the machine. Fig. 3 is a plan view of the parts 10 below the throat-plate; the latter being shown in dotted lines. Figs. 4 to 7, inclusive, are bottom plan views illustrating the action of the stitch-tightening implement and Fig. 8 is a top plan view of the parts 15 shown in Fig. 6.

In the specific embodiment of the invention chosen for the purposes of the present disclosure, 1 indicates the machine bed from which rises the standard 2 of the bracket-arm 3 terminating in the hollow head 4 for the usual reciprocating needle-bar 5 and twin presser-bars 6-6; the former carrying the eye-pointed needle 7 and the latter the presser-feet 8-8. Supported at an elevation 20 above the bed 1, upon the bearing standards 9-9', is the cloth-plate 10 into which is let the usual throat-plate 11 having the slots 12 through which the feed-dog sections 13 operate in a manner well known. The throat-plate 11 is also formed with the usual needle-slot 14 and stitch tongue 15.

Cooperating with the needle 7 is the thread-carrying looper 16 which is oscillated about the looper-shaft 17 by means of the 35 usual pitman connection 17^a with an eccentric 17^b upon the main-shaft s. Since the looper-shaft 17 is horizontally disposed and is inclined forwardly toward the line of feed, it follows that the path of the advancing 40 looper is also inclined forwardly toward the line of feed.

In the present instance, the looper 16, which is formed with the usual thread delivering eye 16', projects its loop through 45 a needle-loop in rear of the needle 7 and moves beyond the edge of the work where the looper-loop is seized by the usual second looper or spreader 18 which, in the present instance, lifts the looper-loop over the edge 50 of the work and presents it for entry by the needle 7 on the next descent of the latter. The spreader 18 is carried by one arm 19 of a bellcrank-lever which is pivoted at 20 to the free end of a link 21 the opposite end of 55 which turns about the downwardly, forwardly and outwardly inclined bearing pin 22 fixed in the lug 23 on the head 4. The other arm 19^a of the bellcrank-lever is connected to the pivoted lever 19^b which is actuated from the main shaft s by means of the eccentric 19^c and pitman 19^d. As the needle, looper and spreader are of the well known construction disclosed, for example, in my Patent No. 1,234,159, of Oct. 16, 1917, 60 further description thereof is believed to 65

be unnecessary. In the present instance, however, I do not make use of the particular looper-thread controller-arm described in said patent as I prefer to lead the looper-thread direct from the tension device 24 to 70 a fixed guide-roll 25 and thence to the blade of the looper. The roll 25, being on that side of the line of feed from which the looper advances, serves to hold the looper-thread so that the looper-blade merely slides along the 75 looper-thread to loop-seizing position without deflecting the looper-thread to any appreciable extent. This will be clear from an inspection of Fig. 1.

The present invention resides more particularly in the take-up or loop-tightening implement 26 which preferably moves transversely of the line of feed in a horizontal plane close to the under side of the throat-plate, as shown in Fig. 1. Referring now 80 to Fig. 3, it will be seen that the stitch-tightening implement is adjustably mounted by means of the slot and screw connection 27 upon the forwardly extended arm 28 of a lever pivoted upon the vertical pin 30 located 85 in rear of the needle and looper and fixed in a lateral lug 31 screwed to the bearing standard 9. The other arm 32 of the stitch-tightener lever carries a ball 33 which is connected by means of a pitman 34 to a ball-eccentric 35 on the main-shaft 5.

The stitch-tightener 26 is forked at its free end to form a smooth surfaced throat 36, Figs. 4 to 8, inclusive, which is moved 100 transversely of the line of seam formation from one side to the other side of the line of needle punctures when viewed in plan, as in Figs. 4 to 8, inclusive. When the throat of the stitch-tightener reaches the line of needle-punctures represented by the 105 tightened needle-loops n, Fig. 5, it catches or forms a bight in the looper-thread t between the looper-eye and the last tightened needle-loop n at the time the looper-eye is crossing the line of needle punctures or, in 110 other words, at the time the looper is entering the nascent needle-loop n'. As the stitch-tightener moves in a direction opposite to that in which the looper is moving, Fig. 6, it pulls the bight of looper thread away 115 from the line of needle punctures and thus pulls the looper-thread t in nearly a straight line, or at a very obtuse angle, through the previously tightened needle-loop n. The path of movement of the throat 120 of the stitch-tightener in passing from one extreme position shown in Fig. 4 to its other extreme position, Fig. 6, intersects the looper-thread at the position shown in Fig. 5. After the stitch-tightener engages the looper thread it continues its motion toward the 125 end of its path and is active or moving to tighten the previous looper-loop. By this action the stitch tightener assists in tightening the previously formed looper-loop t neat- 130

ly about the limbs of the new needle-loop n' at the upper side of the work. The stitch-tightener eccentric 35 is so timed relative to the spreader eccentric 19^c that the stitch-tightener 26, in moving from the position shown in Fig. 6, to that shown in Fig. 7, will give up and release the looper thread t as it is taken by the spreader 18 and thus prevent undue straining of the looper thread by the spreader before the looper thread is released by the stitch tightener. This provision for independent timing of the stitch-tightener relative to the spreader is an important feature which permits a well formed stitch to be secured without unduly straining the looper-thread. It will be observed that at no time is there a stitch-tightening strain imposed upon one of the sewing threads while it is bent sharply or at an acute angle about another sewing thread. Being mounted in rear of the looper, the present stitch-tightener and its operating mechanism do not interfere with the threading of the looper and require no special guards or covers to prevent contact of the work therewith.

While the above described timing of the parts is deemed preferable, the invention is not to be understood as limited to the exact timing described as it may be varied more or less by those skilled in the art, within the scope of the invention defined in the appended claims.

Having thus set forth the nature of the invention, what I claim herein is:—

1. In a sewing machine, the combination with overedge stitch-forming mechanism including a reciprocating needle and a thread-carrying looper, of a stitch-tightening implement, and means for moving said implement in a direction contrary to the direction of advance of the looper, said implement acting to form a bight in the looper-thread leading from the eye of the looper to the previous needle-loop and move said bight of looper-thread away from the line of needle punctures.

2. In a sewing machine, the combination with overedge stitch-forming mechanism including a reciprocating needle and a thread-carrying looper, of a stitch-tightening implement, and means for moving said implement in a horizontal plane in a direction contrary to the direction of advance of the looper, to seize the looper-thread leading from the eye of the looper to the previous needle-loop and pull the slack looper-thread in the previous looper-loop through the previous needle-loop.

3. In a sewing machine, the combination with overedge stitch-forming mechanism including a reciprocating needle and a thread-carrying looper, of a stitch-tightening implement pivotally mounted on a vertical axis in rear of the needle and looper, and means

for moving said implement in a direction substantially opposite to the direction of advance of the looper, to seize the looper-thread leading from the eye of the looper to the previous needle-loop and pull the slack looper-thread in the previous looper-loop through the previous needle-loop.

4. In a sewing machine, the combination with overedge stitch-forming mechanism including a reciprocating needle and a looper, of a stitch-tightening implement, and means for moving said implement from one side to the other side of the line of needle-punctures contrary to the direction of advance of the looper, said implement being positioned and timed to engage the looper-thread leading from the looper-eye to the last stitch during the advance of the looper.

5. In a sewing machine, the combination with overedge stitch-forming mechanism including a reciprocating needle and a looper, of a stitch-tightening implement, and means for moving said implement from one side to the other side of the line of needle-punctures contrary to the direction of advance of the looper, said implement being adapted to form a bight in the looper-thread leading from the looper-eye to the last stitch and pull it away from the line of needle-punctures, thereby tightening the previous looper-loop.

6. In a sewing machine, the combination with overedge stitch-forming mechanism including a reciprocating needle and a looper, of a stitch-tightening implement pivotally mounted in rear of the needle and looper and adapted to engage the looper-thread between the looper-eye and the last stitch to assist the looper in tightening the previous looper-loop.

7. In a sewing machine, the combination with overedge stitch-forming mechanism including a reciprocating needle and a looper, of a stitch-tightening implement pivotally mounted in rear of the needle and looper and forked at its extremity to engage the looper-thread between the looper-eye and the last stitch substantially as and for the purpose specified.

8. In a sewing machine, the combination with overedge stitch-forming mechanism including a reciprocating needle and a looper, of a stitch-tightening implement having a thread-engaging throat and means for moving said implement so that its throat moves from one side to the other side of the line of needle-punctures at a position between the looper and the last stitch, said implement operating to seize the looper-thread and assist the looper in tightening the previous looper-loop.

9. In a sewing machine, in combination, a reciprocating needle, a looper and an overedge implement, a main-shaft, operative connections between the main-shaft and said

4
looper and overedge implement, a stitch-tightening implement adapted to engage the looper-thread between the looper-eye and the last stitch, and an operative connection 5 between the main-shaft and said stitch-tightening implement, said last mentioned operative connection being separate and distinct from the operative connections between the main-shaft and the overedge implement, 10 whereby the stitch-tightener may be closely timed relatively to said implement.

10. In a sewing machine, in combination, a reciprocating needle, a looper, an overedge implement and a stitch-tightener adapted to 15 engage the looper-thread between the looper-eye and the last stitch, a main-shaft, an eccentric on said shaft and connections for operating the looper, a second eccentric on said shaft and connections for operating 20 said overedge implement, and a third eccentric on said shaft and connections for operating the stitch-tightener.

11. In a sewing machine, the combination with overedge stitch-forming mechanism including a reciprocating needle and a thread-carrying looper, of a stitch-tightening implement, and means for moving said implement contrary to the direction of advance of the looper, said implement being constructed and arranged to engage and form 25 a bight in the looper-thread close to the previous needle-loop and pull the looper-thread at an obtuse angle through the previous 30

needle-loop, whereby the previous looper-loop may be tightened under a light tension. 35

12. In a sewing machine, the combination with feeding mechanism and overedge stitch-forming mechanism including a reciprocating needle and a thread-carrying looper operating in a path inclined forwardly 40 toward the line of feed, of a stitch-tightening implement, and means for moving said implement to engage the looper-thread and pull it at an obtuse angle through the previous needle-loop during the tightening of 45 the looper-loop.

13. In a sewing machine, the combination with overedge stitch-forming mechanism including a reciprocating needle, a thread-carrying looper and a spreader, of a stitch-tightening implement having a looper-thread engaging throat, and means for so moving said implement that its throat will traverse a path directed contrary to the direction of advance of the looper and intersecting the looper-thread between the looper and the previous needle-loop, the path of movement of said throat extending beyond the point of first engagement of said throat with the looper-thread, whereby said implement will continue its motion after seizing the looper-thread and will be active in tightening the previous looper-loop. 55 60

In testimony whereof, I have signed my name to this specification.

ALFRED GRIER
